UNITED STATES PATENT OFFICE.

ROBERT P. FRYE, OF MARLBORO, MASSACHUSETTS.

INNER SOLE.

Application filed May 19, 1928. Serial No. 279,173.

The invention relates to inner soles for welted shoes, and it has for its object to produce a desirably inexpensive inner sole, having sufficient strength and stability to hold the upper in the form imparted to it by the lasting operation.

Other objects appear from the following description of my improved inner sole and the statement of the advantages thereof.

10 Of the accompanying drawings forming a part of this specification,—

Figure 1 is a bottom view of an inner sole embodying the invention, looking toward the side from which the inseam stitch-receiving rib projects, portions of the two flexible strips constituting the rib and the anchoring apron hereinafter described, being shown by full lines, and other portions by dotted lines.

20 Figure 2 is a section on line 2—2 of Figure 1.

Figure 3 is an enlargement of a portion of Figure 2.

25 Figures 4 and 5 are fragmentary perspective views, each showing on a much enlarged scale a portion of the inner sole body, and portions of the two flexible strips, said strips being in approximately the forms they assume and the positions they occupy in relation to the insole body before the completion 30 of the rib, Figure 5 showing a slight modification.

Figure 6 is an enlarged fragmentary sectional view, showing the flexible strips in substantially the positions they occupy during the stitching operation.

The same reference characters indicate the same parts in all of the figures.

35 The insole body 12 may be of any suitable material, or combination of materials, and may include an inner layer of leather, and an outer layer of some cheaper material, such as leather board.

40 The body is provided with an inseam stitch-receiving rib, spaced inwardly from the margin of the body, as usual in insoles for welted shoes. With the body and rib is associated an anchoring apron secured to the body at the inner side of the rib and constituting a feature of my improvement.

45 The rib is laminated and the anchoring apron is integral with one of the layers of the rib. The rib and apron are composed of two flexible strips, preferably of textile fabric, such as cotton duck, and each strip 50 may be a length of woven tape having sel-

vage edges, or it may be cut from sheet material and have a raw edge or edges, one set of the crossing threads being preferably parallel with the longitudinal edges of the strip, so that the strip differs from one which is "cut on the bias".

55 One of the strips which I call the outer strip, is folded longitudinally to form two contacting layers 13 and 14 of the laminated rib, and a neck 15 connecting said layers, and secured by a row of outer stitches 16 to the body, the stitches being spaced from the margin of the body and extending substantially parallel therewith. The layer 13 is 60 the outer layer, and the layer 14 an intermediate layer of the rib. The other strip which I call the inner strip, is bent or partially folded longitudinally, so that its cross section is angular, the inner strip including 65 an anchoring apron 17, which is secured to the body 12 at the inner side of the rib, and a flap 18, which contacts with the intermediate rib layer 14, and constitutes the inner 70 layer of the rib, the latter being therefore 75 composed of three plies or layers.

75 The outer edge portion of the anchoring apron 17 is secured to the body by a row of inner stitches 19, extending parallel with the outer stitches 16 and spaced inwardly 80 therefrom. The parallel rows of stitches 16 and 19 may be formed simultaneously by a suitable two-needle sewing-machine, preferably of the lock-stitch type, the two strips being guided simultaneously to the body, 85 and located thereon substantially as indicated by Figure 6, so that the two strips are secured by a single operation. If desired, the bend or neck connecting the portions 17 and 18 of the inner strip, may project slightly 90 into the path of the needle employed in forming the stitches 16, so that said stitches secure the inner portion of the anchoring apron 17 to the body, as shown by Figure 5.

95 The rib layers are united to each other, so that they form a rib of sufficient thickness projecting from one side of the body. This union is effected preferably by providing the outer strip which includes the rib layers 13 and 14, with an adhesive coating 20, indicated by heavy black lines in Figures 3, 4, 5 and 6, and by providing the inner strip 100 with a similar coating 21.

105 The strips may be prepared by spreading on one side of each strip any suitable fluid or semi-fluid material, which is adherent to the strip, and allowing the material to dry,

the nature of the material being such that it is adapted to be rendered substantially non-sticky by drying, and to be softened and rendered sticky or tacky by heat. A suitable material is known to the trade as "gem coating" or "guttasiac", and may contain 55 gutta percha, or some other form of rubber.

After the stitching operation, the previously dried and hardened coatings are rendered soft and sticky by heat, and while the 10 coatings are in this condition, the strips are acted on by a lip-setting machine which presses the sticky coatings on the lip layers 13, 14 and 18 together, and the sticky coating 15 on the apron 17 against the body, so that the lip layers are caused to firmly adhere to each other and form a suitably stiff lip, and the apron is caused to firmly adhere to the body.

20 The layers 13, 14 and 18 are narrower than the apron 17, so that the layers may be temporarily displaced and lie substantially flat on the body, as shown by Figure 6, and on a sewing-machine bed plate to expose the 25 stitch-receiving portions of the two strips, during the stitching operation.

The displaced strips are so located on the body 12 while being stitched, that the edge 30 of the apron, which receives the stitches 19 is exposed, to receive said stitches and the neck portion of the outer strip is exposed to receive the stitches 16, the rib layers 14 and 18 partly, but not entirely overlapping the apron.

35 The inner strip is folded when first applied to the body, the apron bearing on the body, and the layer 18 on the apron, and the outer strip is substantially flat when first applied to the body, its rib layer 14 overlapping the layer 18, all as shown by Figure 6. The bed or throat plate of the sewing- 40 machine may, therefore, be flat, as usual, it being unnecessary to provide a bed plate which is specially formed or recessed to accommodate the material being stitched.

45 The inner sole made as above described, possesses the following combination of advantages over any others of which I am aware:

50 The rib is secured to the body not only by

the stitches 16, but also by the anchoring apron 17, the latter being so firmly secured to the body that it may be much narrower than the width of the body, as shown by Figure 1, a marked saving of material being 55 thus effected.

The inner row of stitches 19 is out of the path of the needle used in forming the inseam stitches and cannot be cut thereby. The marginal portion of the under side of the 60 body from which the rib projects, and on which the shoe upper bears, is exposed, there being no fabric thereon.

The inner row of stitches 19 so confines the outer edge portion of the anchoring 65 apron that it is not liable to be pulled away from the body during the inseam stitching operation.

The two strips constituting the rib and the anchoring apron are secured to the body by 70 two parallel rows of stitches simultaneously formed, so that the time required by the stitching operation is reduced to a minimum.

I claim:

A reinforced insole of the character stated, 75 comprising a body, a flexible outer strip folded to form an outer and an intermediate rib layer and a neck connecting said layers, outer stitches extending approximately parallel with and spaced from the margin of the body 80 and securing the neck thereto, a flexible inner strip including an apron superimposed on the body, and an inner rib layer standing at an angle to the apron, and inner stitches extending parallel with and spaced inwardly 85 from the outer stitches and securing the inner edge portion of the inner strip to the body, means for securing the outer and intermediate rib layers to each other and the inner layer to the intermediate layer, the 90 apron being wider than the several rib layers, so that the intermediate and inner layer may be temporarily located parallel with each other and with the body to expose the stitch-receiving portions of the two strips, and permit the simultaneous formation of the outer and inner stitches.

In testimony whereof I have affixed my signature.

ROBERT P. FRYE.
